[57] CLAIM

The ornamental design for a go-cart guard rail, as shown and described.

DESCRIPTION

FIG. 1 is a top plan view of a go-cart guard rail, showing my new design, the ends broken away to indicate an article of indefinite length.

FIG. 2 is a side elevation of the present go-cart guard rail, showing my new design.

The dominant features of my new design are a plurality of spaced cylinders with a thin plain strip extending therebetween and contacting a peripheral segment of the outer surface of each cylinder.

The hatch lines on the bottom of FIG. 2 are not part of applicant's design but are used to illustrate a surface which supports applicant's design.
